(57) **CLAIM**

The ornamental design for a protective case with stand for tablet computer, as shown and described.

DESCRIPTION

FIG. 1 is a front elevational view of a protective case with stand for tablet computer showing my new design; FIG. 2 is a rear elevational view thereof; FIG. 3 is a left side view thereof; FIG. 4 is a right side view thereof; FIG. 5 is a top plan view thereof; FIG. 6 is a bottom plan view thereof; FIG. 7 is a front perspective view thereof; FIG. 8 is a rear perspective view thereof; FIG. 9 is a front perspective view thereof, shown in an alternative configuration of use; and, FIG. 10 is a rear perspective view thereof. The broken lines shown in protective case with stand for tablet computer form no part of the claimed design.

1 Claim, 10 Drawing Sheets
